PARKING METER RESETTING APPARATUS

Joseph W. Cruse, Tuscaloosa, Ala., assignor of fifty-two percent to J. P. Burchfield, twelve percent to Mrs. Nell M. Burchfield, twelve percent to Wilbur Manderson Burchfield, twelve percent to Joe Lee Burchfield, and twelve percent to Joseph Pegues Burchfield III, all of Tuscaloosa, Ala.

Application May 23, 1955, Serial No. 510,464

7 Claims. (Cl. 194—1)

This invention relates to parking meter resetting apparatus and has for an object the provision of improved means for returning the indicator member of the parking meter to zero position at the time a vehicle leaves the parking space controlled by the meter, whereby no unused time is left showing on the meter and a second vehicle entering the parking space will not obtain free parking for the unexpired period of time paid for by the previous occupant of the parking space.

Another object of my invention is to provide parking meter resetting apparatus which is adapted for use on conventional type parking meters now in use without materially altering the construction of the same.

A further object of my invention is to provide parking meter resetting apparatus of the character designated which is actuated by a shock resistant treadle member positioned in the path of a parking vehicle whereby the meter is rendered operative upon the entrance of a vehicle and the indicator member of the meter is returned to zero position immediately the vehicle leaves the parking space, thus making the meter operable only while a vehicle occupies the parking space.

Briefly my improved resetting apparatus for parking meters comprises a drive shaft connected non-rotatably to the driving means for the meter and adapted for axial movement relative thereto. A clutch member connects the drive shaft to the indicator member and is operable upon axial movement of the drive shaft. The drive shaft is moved axially by an actuating member in position to be operated by a vehicle as it enters the parking space, whereby the drive shaft is moved axially in a direction to engage the clutch while a vehicle is in the parking space and is moved in the opposite direction to disengage the clutch upon removal of the vehicle from the parking space. A coin slot cover member is operatively connected to the actuating member whereby the coin slot is covered while there is no vehicle in the parking space.

Apparatus embodying features of my invention is shown in the accompanying drawing, in which:

Fig. 1 is an elevational view;

Fig. 2 is a sectional view taken generally along the line II—II of Fig. 1, showing the clutch in disengaged position and showing the turn knob and coin operated toggle assembly rotated 90° from their normal positions and without the deposit of a coin;

Fig. 3 is a view taken along the line III—III of Fig. 1, certain parts being broken away and in section;

Fig. 4 is a view similar to Fig. 3, showing a slightly modified form of treadle member; and

Fig. 5 is an enlarged detail view showing the mechanism for operating the coin slot cover member.

Referring now to the drawing for a better understanding of my invention, I show a parking meter indicated generally at 10 which is of the conventional spring motor type. The meter is mounted on a post 11 which is anchored to a sidewalk 12 adjacent the curbing 13 of the street 14, the adjacent portion of which is employed as a parking space.

2

The meter 10 comprises the usual housing 16 having coin slots 17 in one side thereof and a stationary dial 18. Associated with the dial 18 is a pointer or indicator member 19 and the usual warning flags 21 which follow the operation of the indicator member 19 whereby they are in view when the indicator member returns to zero position.

Mounted for rotation in the side of the housing 16 adjacent the coin slot 17 is a short shaft member 22. 10 Mounted on the shaft 22 outwardly of the housing 16 is an operating handle 23. Mounted on the inner end of the shaft 22 is a coin operated toggle assembly 24 which engages a stationary cam member 26 when a coin is deposited and the operating handle 23 is rotated in a clockwise direction, as viewed in Fig. 1. As the toggle assembly is thus rotated, a portion 27 at the free end thereof moves into engagement with a time selecting gear 28 thus causing rotation of the same an angular distance which is determined by the coin deposited. The time selector gear 28 is mounted non-rotatably on a shaft 29 which carries a timing cam 31 and the warning flags 21, in the usual manner. The timing cam 31 engages the indicator member 19 and moves the same about a pivot pin 32 in a counterclockwise direction as the operating handle 23 is moved in a clockwise direction. As shown in Fig. 2, a spring 33 urges the indicator member 19 toward zero position.

The apparatus described above is the conventional type apparatus now employed on spring motor type meters.

30 My improved apparatus for resetting the meter is associated with the mechanism described above in a manner now to be described.

Secured to the side wall of the housing 16 opposite the operating handle 23 is an auxiliary housing 34. Extending through the housing 34 and the housing 16 and mounted for rotation in suitable bearings 36 and 37 is a horizontal drive shaft 38. Mounted within the housing 16 adjacent the auxiliary housing 34 is a spring motor unit indicated generally at 39. The spring motor is provided with a coil spring 41 which is secured at one end by a pin 42 to a stationary plate member 43 which in turn is secured to the housing 16 by means of rivets 44. The other end of the coil spring is secured to a drive gear 46 by means of a bolt 47. The drive gear 46 is provided with an axially extending sleeve portion 48 which is splined internally for slidably receiving a splined portion 49 of the drive shaft 38. The drive shaft is thus connected non-rotatably to the gear 46 and is adapted for axial movement relative thereto.

50 Mounted on the inner end of shaft 29 is a crown gear 51 and mounted on the inner end of the drive shaft 38 is a second crown gear 52. The crown gears 51 and 52 thus face each other and define a crown gear type clutch for connecting and disconnecting the shaft 29 and the drive shaft 38. The drive shaft 38 is provided with a reduced diameter portion 53 which is disposed to fit in an axially extending opening 54 provided in the shaft 29. Surrounding the shaft 29 intermediate the crown gears 51 and 52 is a compression spring 56 which urges the crown gear 52 away from the crown gear 51, as shown in Fig. 2.

55 Mounted for rotation on the drive shaft 38 within the auxiliary housing 34 is a cam member 57. Axial movement of the cam member 57 relative to the drive shaft 38 is limited by inwardly projecting pin members 58 which ride in an annular groove 59 formed in the outer surface of the drive shaft. Secured to the housing 34 outwardly of the cam member 57 is a second cam member 61 which slidably receives the drive shaft 38 and is provided with a cam surface corresponding to that of the cam member 57 whereby the drive shaft 38 is moved axially as the cam member 57 is rotated.

70 Mounted on the curb 13 is a suitable housing 62 for

a shock resistant treadle type actuating member. The housing 62 is secured to the curb by any suitable means, such as by bolts 63. The actuating member embodies an angular shaped arm 64, as viewed in plan. One end of the arm 64 is pivotally connected to the housing 62 by means of a pivot pin 66. The arm 64 is urged outwardly of the housing 62 and over the parking space 14, as shown in Fig. 1, by means of a spring member 67 which surrounds the pivot pin 66 and is anchored at one end to the swing end of the arm 64 by means of a pivot pin 68. The other end of the spring 67 is anchored to the housing 62 by means of a pin 69. As shown in Fig. 3, the legs of the angular shaped arm 64 form an obtuse angle which overlies the parking space with the legs of the angle directed away from the parking space. By providing such a construction, vehicles can park parallel to the curb 13 without the liability of damage to the actuating member. The end of the arm 64 adjacent the pivot pin 66 is provided with a cam surface 71. Secured to the arm 64 as at 72 is a flexible cable 73 which passes around the cam surface 71. The other end of the cable 73 is secured as at 74 to the cam member 57 mounted on the drive shaft 38. The flexible cable 73 passes through a tubular housing member 76 mounted alongside the post 11 and secured thereto by suitable strap members 77. It will thus be seen that as the arm 64 is moved inwardly by the wheel of a vehicle, the cable 73 passing around the cam surface 71 rotates the cam member 57 thereby causing axial movement of the drive shaft 38 inwardly toward the left, as viewed in Fig. 2, whereby the crown gear 52 moves into engagement with the crown gear 51.

Pivotedly connected to a pivot pin 78 on the inner wall of the housing 16 adjacent the coin slot 17 is a coin slot cover member 79. The cover member 79 is provided with an inwardly projecting arm 81 having a link 82 pivotally connected thereto. The drive shaft 38 is provided with a second reduced diameter portion 83 which projects through a suitable opening 84 at the end of the shaft 29. The shaft 38 is reduced further in diameter at the end thereof as at 86 for slidably receiving one end of an arm 87. The arm 87 is held against axial movement relative to the drive shaft 38 by means of a collar 88 and set screw 89. The other end of the arm 87 is provided with a sleeve like bearing member 91 which receives a rod like guide member 92 secured rigidly to the housing 16. The drive shaft 38 is thus free to rotate relative to the arm 87 and the arm moves with the shaft as the shaft is moved axially. The link 82 is pivotally connected to the arm 87 by means of a pivot pin 93 whereby the coin slot cover member 79 is moved to the dotted line position as the drive shaft 38 is moved to the left, as viewed in Fig. 5.

Secured to the gear 46 of the spring motor 39 is an axially extending pin 94. Mounted on the plate 43 in position to engage the pin 94 is a stop member 96 which permits the gear 46 to rotate in a direction to unwind the meter driving spring to a predetermined tension so that subsequent operation of the meter will not wind the spring too tightly.

In Fig. 4 I show a slightly modified form of actuating member in the form of an arm 64a pivotally mounted adjacent one end to a pivot pin 66a. A spring 67a passes around the pivot pin 66a and is secured to the swing end of the arm 64a by means of a pivot pin 68a. The other end of the spring 67a is anchored by means of a pivot pin 69a to the housing indicated at 62a. The arm 64a is provided with a cam surface 71a adjacent the pivot pin 66a around which the flexible shaft 73 passes. The shaft 73 is secured to the arm 64a as at 72a whereby the cam member 57 is rotated as the arm 64a is moved inwardly by the wheel of a vehicle. The actuating member shown in Fig. 4 is particularly adapted for diagonal parking.

From the foregoing description, the operation of my improved parking member resetting apparatus will be readily understood. To park a vehicle, it is driven into the parking space whereupon the right front wheel thereof

engages the arm 64 or 64a, as the case may be, thereby pulling the flexible cable 73 and in turn rotating the cam member 57. As the cam member 57 is rotated, the drive shaft 38 is moved axially to the left, as viewed in Fig. 2, causing the crown gear 52 to engage the crown gear 51, thereby connecting the spring motor 39 to the time selector gear 28. As the drive shaft 38 is moved axially to the left, the arm 87 is shifted in a direction to cause rotation of the coin slot cover member 79 to the dotted line position, as shown in Fig. 5. Upon depositing a coin in the coin slot 17 and then rotating the operating handle 23 the portion 27 of the coin operated toggle 24 moves into engagement with the time selector gear 28 thereby connecting the operating handle 23 to the spring motor 39. Continued rotation of the operating handle 23 causes the spring motor 39 to be wound. As the shaft 29 is rotated, the timing cam 31 engages the indicator member 19 thereby moving the same about its pivot pin 32 whereby it indicates the amount of parking time on the meter dial 18. Also, as the shaft 29 is rotated, the warning flags 21 move downwardly out of sight, in the usual manner. It will be understood that the portion 27 of the coin operated toggle 24 will not move into engagement with the time selector gear 28 until a coin is deposited in the slot 17. That is, the coin operated toggle 24 operates independent of the time selector gear 28 when there is no coin deposited, as shown in Fig. 2.

When the vehicle leaves the parking space, pressure on the treadle actuating member 64 or 64a, as the case may be, is released whereupon the cam 57 is free to rotate to its original position due to the pressure exerted against the same by the compression spring 56. That is to say, the compression spring 56 moves the crown gear 52 out of engagement with the crown gear 51 and shifts the splined drive shaft 38 axially to the right, as viewed in Fig. 2, relative to the spring motor 39. At this time, the indicator member 19 is disconnected from the spring motor thus permitting the spring 33 to return the same to zero position, as shown in Fig. 1. Also, at this time the warning flag 21 moves to the raised position whereby it is in view, as shown in Fig. 1. Also, as the drive shaft is moved axially to the right, as viewed in Fig. 2, the arm 87 moves with the same thereby moving the coin slot cover member 79 to the solid line position whereby the mechanism will not accept a coin until the treadle actuating member 64 is depressed again. After the spring motor 39 has been disengaged from the indicator member, it unwinds to a predetermined tension, determined by the stop member 96, whereby subsequent operation thereof will not wind the same too tightly.

From the foregoing, it will be seen that I have devised improved resetting mechanism for parking meters which is adapted for installation on conventional type parking meters with a minimum of changes therein. By providing means for disengaging the indicator member from the driving means the instant the vehicle leaves the parking space, the indicator member moves by its own spring tension to zero position thereby making it necessary for each user of the parking space to make payment therefor. Furthermore, by providing means preventing the deposit of a coin until the vehicle is properly parked, I eliminate entirely the possibility of the user losing his coin without the proper amount of time being registered on the meter.

While I have shown my invention in but two forms, it will be obvious to those skilled in the art that it is not so limited, but is susceptible of various other changes and modifications without departing from the spirit thereof, and I desire, therefore, that only such limitations shall be placed thereupon as are specifically set forth in the appended claims.

What I claim is:

1. The combination with a meter for a parking space including an indicator member urged normally toward zero position and spring drive means for progressively

advancing said indicator member whereby the elapsed time is indicated, of a drive shaft connected non-rotatably to said drive means and adapted for axial movement relative thereto, a clutch interposed between said drive shaft and said indicator member and operable to connect said indicator member to said drive shaft upon axial movement of the drive shaft in one direction, an actuating member in position to be operated by a vehicle, and mechanical means operatively connecting said actuating member to said drive shaft whereby the drive shaft is moved axially in a direction to engage the clutch and connect the indicator member to the drive shaft while a vehicle is in the parking space and is moved in the opposite direction to disengage the clutch upon removal of the vehicle from said space whereupon the indicator member is free to move to zero position.

2. The combination with a meter for a parking space including an indicator member urged normally toward zero position and a spring motor for progressively advancing said indicator member whereby the elapsed time is indicated, of a drive shaft keyed non-rotatably to said spring motor and adapted for axial movement relative thereto, a clutch interposed between said drive shaft and said indicator member and operable to connect said indicator member to said drive shaft upon axial movement of the drive shaft in one direction, a cam member mounted for rotation on said drive shaft, means limiting axial movement of said cam member relative to said shaft, a stationary cam surface engaging said cam member whereby upon rotation of the cam member said drive shaft is moved axially, an actuating member in position to be operated by a vehicle, mechanical means operatively connecting said actuating member to said cam member whereby the drive shaft is moved axially in a direction to engage the clutch and connect the indicator member to the drive shaft while a vehicle is in the parking space and is moved in the opposite direction to disengage the clutch upon removal of the vehicle from said space whereupon the indicator member is free to move to zero position, and means limiting the unwinding action of said spring motor whereby its spring is unwound to a predetermined tension through its normal operation.

3. Apparatus as defined in claim 2 in which the actuating member is a treadle member connected to the cam member by a flexible cable.

4. Apparatus as defined in claim 3 in which the treadle member comprises an arm pivotally mounted adjacent one end to a stationary member with the free end thereof projecting over the parking space in position to be engaged by a vehicle.

5. Apparatus as defined in claim 4 in which the treadle member comprises an angular shaped arm as viewed in plan pivotally mounted at one end to a stationary member

and defining an obtuse angle overlying an edge of the parking space with the legs thereof directed away from the parking space.

6. The combination with a meter for a parking space including an indicator member urged normally toward zero position and spring drive means for progressively advancing said indicator member whereby the elapsed time is indicated, of a drive shaft connected non-rotatably to said drive means and adapted for axial movement relative thereto, a first crown gear operatively connected to said indicator member, a second crown gear mounted non-rotatably on said drive shaft and disposed to engage said first crown gear upon axial movement of the drive shaft in one direction and disengage said first crown gear upon axial movement of the drive shaft in the opposite direction, means urging said drive shaft toward said opposite direction, an actuating member in position to be operated by a vehicle, and mechanical means operatively connecting said actuating member to said drive shaft whereby the drive shaft is moved axially in the direction to engage said crown gears while a vehicle is in the parking space and releases said drive shaft for movement in the opposite direction upon removal of the vehicle from said space.

7. The combination with a coin actuated meter for a parking space including an indicator member urged normally toward zero position, drive means for progressively advancing said indicator member whereby the elapsed time is indicated and a coin slot cover member, of a drive shaft connected non-rotatably to said drive means and adapted for axial movement relative thereto, a clutch connecting said drive shaft to said indicator member and operable upon axial movement of the drive shaft, an actuating member in position to be operated by a vehicle, means operatively connecting said actuating member to said drive shaft whereby the drive shaft is moved axially in a direction to engage the clutch while a vehicle is in the parking space and is moved in the opposite direction to disengage the clutch upon removal of the vehicle from said space, an arm having an opening through one end thereof for slidably receiving a portion of the drive shaft, means limiting axial movement of said arm relative to said shaft, and a link connection between said arm and the coin slot cover member.
